CLAIM

The ornamental design for a table ornament, as shown and described.

DESCRIPTION

The patent or application file contains at least one photograph executed in color. Copies of this patent with color photographs will be provided by the office upon request and payment of the necessary fee.

FIG. 1 is a front, right, and top view of a table ornament, showing my new design;

FIG. 2 is a front, left, and top view thereof;

FIG. 3 is a rear, right, and top view thereof;

FIG. 4 is a rear, left, and top view thereof;

FIG. 5 is a rear, left, and bottom view thereof;

FIG. 6 is a front view thereof;

FIG. 7 is a rear view thereof;

FIG. 8 is a right side view thereof;

FIG. 9 is a left side view thereof;

FIG. 10 is a top view thereof; and,

FIG. 11 is a bottom view thereof.
